WILLIAM FAGERGREN, OF SALT LAKE CITY, UTAH, AND WILLIAM D. GREEN, OF BUTTE, MONTANA, ASSIGNEES, BY MESNE ASSIGNMENTS, TO METALS RECOVERY COMPANY, A CORPORATION OF MAINE.

ORE-CONCENTRATOR.

1,195,453.

Specification of Letters Patent. Patented Aug. 22, 1916.

Application filed August 12, 1918. Serial No. 784,336.

To all whom it may concern:

Be it known that we, WILLIAM FAGERGREN and WILLIAM D. GREEN, citizens of the United States, and residents, respectively, of Salt Lake City, in the county of Salt Lake, State of Utah, and Butte, in the county of Silverbow and State of Montana, of the United States of America, have invented a new and useful Improvement in 10 Ore-Concentrators, of which the following is a specification.

Our invention relates to apparatus for the concentration of ores, our more particular purpose being to produce a device of improved construction for concentrating ores, such for instance, as sulfids, by aid of the process known in this art as flotation by aid of air.

More particularly, we provide an apparatus for introducing air into a body of ore pulp or comminuted ore contained in water, so as to cause all concentrates in the form of minute particles, to be floated by aid of air bubbles, and we also provide improved means for separating the particles thus floated and also means for separating the residual gangue from the pulp or its equivalent.

Reference is made to the accompanying drawing forming a part of this specification, and in which like characters indicate like parts.

Figure 1 is a side view partly in elevation and partly in section showing one representative form of our improved apparatus. Fig. 2 is a plan view of one of the ore concentrating units shown in Fig. 1. Fig. 3 is a horizontal section on the line 3—3 of Fig. 1, looking in the direction of the arrows.

We provide corner posts 4 made preferably of angle iron, and connected with these corner posts are walls 5. Brace rods 6 extend from one corner post to another and serve in connection with the posts for holding the walls securely in position. These brace rods carry revoluble nuts 7 for facilitating their application. Located at the bottom of the walls 5 is a floor 8. The corner posts, walls and bottom 8 collectively constitute a type 50 of tank, which, with its accompanying parts, we conveniently designate as a unit or distinct machine. Any number of these machines may be connected up, two of them

being shown in Fig. 1. Mounted upon the several tanks, and partially encircling the 55 tops thereof, are drain boxes 9—10 provided respectively with discharge spouts 11—12, these discharge spouts extending, if desired, in opposite directions as indicated in Fig. 1.

Each tank carries a spider 13, the latter 60 being provided with bearings 14—15, and supported upon the tank by aid of fastenings 16, as shown in Fig. 1. The wall 5 of each tank is provided with a beveled edge 16^a, encircling the base of the spider. A 65 square tub 17 is located within the bottom portion of the tank and is provided with a sharp upper edge 18—that is, this edge is beveled. An ore pipe is shown at 19 and to it an air pipe 20 is connected. The air pipe 70 is provided with a valve 21. The ore pipe at a point just above the air pipe extends upwardly into the center of the tank.

From each tank to the next successive tank extends a pipe 22 provided with a valve 23, 75 and connected with this pipe is an air pipe 24 provided with a valve 25. The pipes 22 and 24 with the valve 25 serve, in connection with the tank with which they are associated, to work the gangue or other crude material, the second time in order to separate 80 from it any residual concentrates which it may contain.

A dasher 26 is located within the tub 17, and is provided with a collar 27, the latter 85 carrying a set screw 28, and by aid of this collar and set screw the dasher is secured rigidly upon the lower end of a vertically disposed shaft 29. This shaft extends through the bearings 14—15. We provide a 90 number of horizontally disposed floors 30, 31, 32, these floors having holes 31^a, 32^a, 33 extending through them. The holes 31^a, 32^a, are inclined relatively to the general plane 95 of the floors but extend in different angular directions. The holes 33 extend vertically through the floor 32. These floors 30, 31, 32, are conveniently designated as baffle floors.

Mounted rigidly upon the shaft 29, at a point between the bearings 14—15, is a 100 pulley 34, and engaging this pulley is a belt 35, which extends to the corresponding pulley 34 of the next successive unit or machine, as indicated in Fig. 1. Mounted upon one of the shafts 29 is a driving pulley 36, 105 and engaging the latter is a driving belt 37.

Each drain box 9—10 is provided with a floor 38, the latter sloping downwardly in opposite directions from a crown 39, for the purpose of facilitating drainage from the drain boxes into the discharge spouts 11—12.

The ore, preferably in the form of liquid pulp, or at least made into finely divided particles mixed with water, is fed into the machine through the ore pipe 19. In forming the pulp, or otherwise preparing the ore, preparatory to the use of our machine, the ore may be, if desired, subjected to the action of chemicals or of other substances for giving it a proper consistency. Frequently sulfuric or oxalic acid is introduced into the pulp and if desired any substances suitable for enabling the ore to be floated may be added. As our invention does not relate particularly to the manner in which the ore is prepared, and as this step of the art is old and well known, we do not describe it in greater detail. The air pipes 20—24 are connected with a suitable supply of compressed air.

The operation of our device is as follows: Each tank is first filled with water. Power being applied by aid of the driving belt 37 and pulley 36 to the shaft 29, the dasher 26 is caused to rotate continuously. The pulp or equivalent ore material is fed continuously through the pipe 19, while air is supplied continuously through the air pipe or pipes as the case may be. The ore upon arriving within the tub 17 is agitated by the dasher 26, and the air is broken up into fine particles which permeate and are partially distributed throughout the ore mass. In this way such fine particles of ore as have any marked tendency to float are caused to adhere to the air bubbles and are carried upwardly by the latter. The particles of ore thus floating are the concentrates. The gangue being unable to float, and yet being agitated continuously by the dasher 26, is carried over the sharp upper edge of the tub 17 and floats or creeps downwardly around this tub and out through the pipe 22, being thus introduced into the next successive tank if one be used. The particles of ore, floated as above described by minute air bubbles, are carried upwardly through the various baffle floors 30, 31, 32 and reach the top of the tank. They are carried over the sharp upper edges 16 of the wall, and thus arriving in the drain boxes 9 are carried off through the discharge spout. The baffle floors 30, 31, 32, being immovable serve to render the liquid comparatively quiescent, or in other words, they prevent further disturbance of the ore particles after they are properly floated. In order to render this action effective, we provide more than one of the floors. In doing this we prevent the ore particles from becoming detached from

the air bubbles after being once connected therewith. The concentrates, which carry with them more or less gangue or crude material, next pass through another machine of the kind just described and in this way a still further refinement may be effected.

Considerable advantage is gained, in our construction of machine, by the fact that the sharp upper edges of the tub 17 and the walls 5 may be made of considerable length without necessitating enlargement of the machine. A considerable overflow path is thus rendered available though the machine as a whole may occupy comparatively close quarters. The construction just mentioned also facilitates the quick removal of the concentrates from a given quantity of ore or equivalent crude material. In this connection it may be noted that in concentrating mills there is frequently but little space allowed for the concentrating machines to occupy, and it is therefore desirable that the greatest efficiency may be developed for a given amount of space occupied by the machines.

Our construction affords another considerable advantage, to wit, that the floating ore particles are removable, in the manner above described, so quickly after reaching the upper level of the tank and before they have time for any material-exposure to the free air of the atmosphere, as to prevent the bubbles from breaking and thus allowing the concentrates to sink. This purpose is still further promoted by the reduction in diameter of the tank at its top.

If for any reason it should happen that a bubble of air carrying a particle of ore should become disengaged from the particle after passing through one or more of the baffle floors the ore particle thus set free cannot readily descend to the bottom of the tank but slowly settles down toward the next successive baffle floor below it, and sooner or later is likely to be picked up by another air bubble passing upwardly.

We do not limit ourselves to the precise construction shown as variations may be made in our machine without departing from the spirit of our invention.

Having thus described our invention we claim as new and desire to secure by Letters Patent as follows:

1. In an ore concentrator, the combination of a tank, a receptacle located within said tank and provided with a wall having a continuous edge from which ore materials may be discharged, means for introducing within said tank and within said vessel ore pulp or the like, means for admitting air into said receptacle, a dasher located within said receptacle for the purpose of agitating said ore pulp and said air, a plurality of baffle floors located at differ-

ent successive levels within said tank and provided with openings, and means for discharging gangue and water overflowing from said receptacle within said tank and 5 means for discharging concentrates from the top of said tank.

2. In an ore concentrator, the combination of a tank provided with an upper edge, a tub located within the bottom portion of 10 said tank and provided with an upper edge, a plurality of baffle floors provided with openings located within said tank and disposed at different successive levels above said tub, a revoluble shaft extending 15 through said tank and said floors and into said tub, a dasher located within said tub and mounted upon said shaft, means for turning said shaft, a pipe for discharging air into the bottom of said tub, and means 20 for admitting into the bottom of said tub a supply of ore pulp to be operated upon by said air and said dasher.

3. In an ore concentrator, the combination of a tank, means for introducing into the 25 lower portion thereof a supply of ore pulp, means for introducing air into the lower portion of said tank, a dasher for agitating said ore pulp and the air supplied thereto, a plurality of baffle floors located at different levels above the bottom of said tank and 30 provided with openings, the openings in one baffle floor extending in different angular directions to the openings in another baffle floor, and means for discharging air 35 floated particles of ore passing upwardly through said openings.

4. In an ore concentrator, the combination of a tank, a receptacle located within 40 said tank and over the upper portion of which ore materials may be discharged, means for introducing within said tank and within said receptacle the ore pulp or the like, means for admitting air into said receptacle, means within said receptacle for 45 agitating the ore pulp and said air, a plurality of baffle floors located at different levels within said tank and provided with openings, means for discharging the gangue and water overflowing from said receptacle 50 within said tank, and means for discharging the concentrates from the upper portion of said tank.

5. In an ore concentrator, the combination of a tank, a receptacle located within 55 the bottom portion thereof, and over the top edge of which the gangue and water will overflow, a plurality of baffle floors provided with openings within said tank and disposed at different successive levels 60 above said receptacle, a shaft extending through said tank and said floors and into said receptacle, an agitator located within said receptacle, and mounted upon said shaft, means for rotating said shaft, a pipe

for discharging air into the lower portion 65 of said receptacle, and means for admitting into the lower portion of said receptacle a supply of ore pulp to be operated upon by said air and said agitator.

6. In an ore concentrator, the combination of a tank, means for introducing into the lower portion thereof a supply of ore pulp, means for introducing air into the lower portion of said tank, a dasher for 70 agitating said ore pulp and the air supplied thereto, a plurality of baffle floors located at different levels above the bottom of said tank and provided with openings, and means for discharging air-floated particles of ore 75 passing upwardly through said openings. 80

7. In an ore concentrator, the combination of a tank, a receptacle located within said tank and provided with a wall having a continuous edge from which ore materials may be discharged, means for introducing 85 within said tank and within said vessel ore pulp or the like, means for admitting air into said receptacle, means for diffusing the air through the pulp, a plurality of baffle floors located at different successive levels 90 within said tank and provided with openings, and means for discharging gangue and water overflowing from said receptacle within said tank and means for discharging concentrates from the top of said tank. 95

8. In an ore concentrator, the combination of a tank, means for introducing into the lower portion thereof a supply of ore pulp, means for introducing air into the lower portion of said tank, means for diffusing 100 the air in the pulp, a plurality of baffle floors located at different levels above the bottom of said tank and provided with openings, and means for discharging air-floated particles of ore passing upwardly through said 105 openings.

9. An apparatus for concentrating ores by gaseous flotation of certain mineral particles in liquid, comprising in combination inner and outer vessels spaced from each 110 other, said inner vessel adapted to receive a substantially deep body of ore pulp; means for admitting ore pulp into said inner vessel, a horizontal centrifugal agitator within the inner vessel near the bottom thereof; 115 means for admitting a gaseous fluid under pressure into the tank below said agitator; and means within the outer vessel and overhanging the vertical sides of said inner vessel for producing a comparatively quiescent 120 zone in the portion of the outer vessel where froth forms, said inner vessel having an overflow at its upper portion for delivering depleted ore particles into the space between said vessels. 125

10. In an apparatus for concentrating ores, the combination of an agitation and separation vessel having inner and outer

walls spaced from each other to form a chamber for tailings, said wall inclosing a central pulp receiving chamber; means for introducing ore pulp into the central chamber, said chamber adapted to contain a substantially deep body of ore pulp and having an overflow in its upper portion connecting with said tailings chamber; means for agitating the pulp in the lower part of the central chamber; means for introducing a gaseous medium into the lower part of said central chamber; means for maintaining the pulp in the upper part of the vessel in a state of comparative quiescence; and means 15 for removing the froth from the top of said vessel.

11. In apparatus for concentrating ores, the combination of inner and outer vessels spaced from each other to form a chamber 20 for receiving depleted ore pulp; means for introducing ore pulp into the inner vessel, said vessel having a top overflow for delivering depleted ore pulp into said chamber; means for removing the depleted ore pulp 25 from said chamber; means for vigorously agitating the pulp within the inner vessel; means for introducing a gaseous medium to the part of the pulp in rapid movement in said inner vessel; and means for maintaining 30 the pulp in the upper part of the outer vessel in a state of comparative quiescence.

12. In an apparatus for concentrating ores, the combination of inner and outer vessels spaced from each other to form a chamber 35 for depleted ore pulp, said inner vessel adapted to contain a deep body of mineral bearing pulp and having an overflow for depleted ore pulp into said chamber; means for introducing ore pulp into the lower part of the inner vessel; means for vigorously agitating the pulp within the inner vessel; means for introducing a gaseous medium to the part of the pulp in rapid movement in said inner vessel; means 40 for maintaining the pulp in the upper part of the outer vessel in a state of comparative quiescence; means for removing depleted ore pulp from said chamber; and means for removing froth from the top of the outer 45 vessel.

13. In an apparatus for concentrating ores, the combination of inner and outer vessels, both open at the top, said inner vessel being spaced from the outer vessel to 55 form therebetween a chamber for depleted ore pulp, and having substantial depth so as to contain a deep body of pulp and having an overflow at its upper portion for depleted ore pulp into said chamber; an inlet conduit for ore pulp leading into the inner vessel; an outlet conduit for tailings leading from the space between the two vessels; a rotatable agitator in the lower part of the inner vessel; a conduit for gaseous me-

dium leading into the lower part of the 65 inner vessel; and substantially horizontal plates in the outer vessel above the inner vessel and forming angles to maintain the pulp in a state of comparative quiescence.

14. In an apparatus for concentrating 70 ores, the combination of an agitating and separation tank, said tank having double walls in its lower portion forming therebetween a chamber for depleted ore pulp, the innermost of said walls inclosing a chamber 75 of substantial vertical depth adapted to contain a deep body of mineral bearing pulp, and having an overflow at the upper portion communicating with said depleted ore pulp chamber; an inlet conduit for ore 80 pulp leading into the chamber inclosed by the innermost wall of the vessel; an outlet conduit for conducting tailings from the chamber between said walls; a rotatable agitator in the lower part of the pulp chamber; 85 a conduit for a gaseous medium leading into the lower part of the pulp chamber; and baffles in the upper part of the vessel and overhanging the pulp receiving chamber and adapted to maintain the pulp in a state 90 of comparative quiescence.

15. In an apparatus for concentrating 95 ores, the combination of an agitation and separation tank, said tank having double walls in its lower portion forming there- 100 between a chamber for depleted ore pulp, the innermost of said walls inclosing a chamber of substantial vertical depth adapt- 105 ed to contain a deep body of mineral bearing pulp, and having an overflow at the up- 110 per portion communicating with said de- 115 pleted ore pulp chamber; an inlet conduit for ore pulp leading into the chamber inclosed by the innermost walls of the vessel; an outlet conduit for conducting tailings from the chamber between said walls; a rotatable agitator in the lower part of the pulp chamber; a conduit for a gaseous medium leading into the lower part of the pulp chamber; baffles in the upper part of the vessel and overhanging the pulp receiving chamber and adapted to maintain the pulp in a state of comparative quiescence; and a concentrates launder arranged at the top of the vessel for continuous removal of froth.

16. In apparatus for concentrating ores, the combination of a vessel having walls 120 which converge toward the upper end, said vessel being open at the top; a second ves- 125 sel within the lower portion of the first ves- 130 sel and spaced from the walls thereof so as to form a chamber for depleted ore pulp, said inner vessel having substantial depth so as to contain a substantially deep body of ore pulp and having a top overflow for de- 135 pleted pulp into said chamber; means con- 140 necting with the chamber between said ves-

sels and serving as a conduit for depleted pulp settling thereinto; a rotatable agitator in the lower part of the inner vessel; means for admitting a gaseous medium into the lower 5 part of the inner vessel; baffles in the upper tapered portion of the outer vessel adapted to maintain the pulp therein in a state of comparative quiescence; and a concentrates

launder at the top of the outer vessel for the continuous removal of froth.
